Primary Examiner — Richard Edgar*Assistant Examiner* — Jessica Ruth Grable(74) Attorney, Agent, or Firm — The Roy Gross Law Firm, LLC; Roy Gross(57) CLAIM

The ornamental design for a hanger, as shown and described.

DESCRIPTION

FIG. 1 is a perspective view of a hanger showing my new design;

FIG. 2 is a right side view thereof;

FIG. 3 is a left side view thereof;

FIG. 4 is a front view thereof;

FIG. 5 is a back view thereof;

FIG. 6 is a top view thereof;

FIG. 7 is a bottom view thereof; and,

FIG. 8 is another perspective view thereof.

The broken lines shown in the FIGS. 4 and 8 are included for the purpose of illustrating environment and form no part of the claimed design. The remaining broken lines represent portions of the hanger and form no part of the claimed design.

1 Claim, 6 Drawing Sheets(56)
